UNITED STATES PATENT OFFICE.

THOMAS VANDERSLICE, OF VALLEY FORGE, PENNSYLVANIA.

IMPROVEMENT IN MEAT-CUTTING-MACHINES

Specification forming part of Letters Patent No. 8,072, dated May 6, 1851.

To all whom it may concern:

Be it known that I, THOMAS VANDERSLICE, of Valley Forge, in the county of Chester and State of Pennsylvania, have invented a new and useful Improvement in Machines for Cutting Meat for Sausages; and I do hereby declare that the following is a full and exact description of the same, reference being had to the annexed drawings, making part of this specification, in which—

Figure 1 is a vertical view of the machine in an open position. Fig. 2 is a transverse section representing especially one of the cutters with its respective adjusting-plate; and Fig. 3 is an end view showing the discharging-aperture and sliding gate.

The principal features of this invention consist in an arrangement for adjusting the positions of the several rotary cutters, so as to keep the edges thereof in contact with the periphery of the cylindrical chamber within which they revolve.

The casing of this machine consists of an oblong cubical trunk A B, the interior of which has the form of a hollow cylinder five inches in diameter, through the longitudinal center of which passes a mandrel c c, which has its bearings at the ends of the trunk, and one end of which is furnished with a crank or pulley. Upon this mandrel, near the right end of the trunk, is mounted a short cylinder D, three inches in diameter, from the periphery of which projects a helical flange e e, which extends to the periphery of the cylindrical chamber. The face or left side of the flange is at right angles with the axle, and the right side has an inclined curve from the apex of the flange to the periphery of the cylinder. Upon the mandrel, between the flanged cylinder and the left end of the trunk, is mounted a series of circular blocks I I I, three inches in diameter and half an inch thick. Between the cylinder D and the right block and between each two of the blocks is adjusted a cutter J and an adjusting-plate K, the cutter and the plate being of equal thickness. The cutter is mounted upon a pivot-pin n, which projects from the left disk of each block. Another pin r projects from the same disk through a curved aperture o o and enters the next succeeding block, and whereby the blocks are secured in their proper

relative positions. In the periphery of the adjusting-plate is a notch s, by means of which the relative position of the plate is occasionally changed, and the position of the cutter, the back of which rests upon a corner t of the adjusting-plate, is thereby also adjusted. A screw-thread is cut upon the mandrel, near the left end thereof, upon which is a circular screw-nut P, by which the entire series of blocks and plates are firmly pressed together, and whereby the latter are held fast in whatever relative position they are placed. The use of the plates is to adjust the cutters in such positions that the most prominent part of the cutting-edge of each may work in close contact with the periphery of the cylindrical chamber.

Through the top of the trunk, (which is equal in dimensions with the bottom and connected thereto by hinges and hasps,) at the right end thereof, is a vertical feeding-aperture I, and through the left end of the trunk is a discharging-aperture X, to which is adapted a sliding gate w, whereby the discharge of the chopped meat is regulated. To the top of the bottom section of the trunk, parallel with the axle and extending from the front to the periphery of the cutter-cylinder, (the series of circular blocks and plates,) is attached a horizontal plate Y, in the rear edge of which is a series of slots Z Z, of sufficient length and breadth to allow the cutters to pass through them, and whereby the latter, as also the periphery of the cutter-cylinder, are cleared from the meat which might otherwise adhere to them. The positions of the several cutters are so arranged as to succeed each other in helical order, as represented in Figs. 1 and 2.

What I claim as my invention, and desire to secure by Letters Patent, is—

The herein-described mode of adjusting the cutters J by means of the adjusting-plates K, as described.

In testimony whereof I have hereunto signed my name before two subscribing witnesses.

THOMAS VANDERSLICE.
